UNITED STATES PATENT OFFICE.

HARVEY C. LOWRIE, OF DENVER, COLORADO.

TOILET-STAND.

SPECIFICATION forming part of Letters Patent No. 354,917, dated December 28, 1886.

Application filed May 8, 1886. Serial No. 201,549. (No model.)

To all whom it may concern:

Be it known that I, HARVEY C. LOWRIE, a citizen of the United States, residing at Denver, county of Arapahoe, and State of Colorado, 5 have invented certain new and useful Improvements in Toilet-Stands, fully described and represented in the following specification and the accompanying drawings, forming a part of the same.

10 This invention relates to that class of toilet-stands or dressing-cases in which, in order to economize room, a wash-stand, or, strictly speaking, a wash-bowl and its attendant accessories, are combined with a bureau or dressing-case, the combination being such that by 15 a manipulation of a top or cover the wash-bowl may be concealed, or exposed for use.

The great desideratum in this class of furniture is to so combine the wash-bowl and arrange 20 the fresh-water tank and waste-receptacle with a stand or bureau that a compact structure is obtained having the outward appearances of a bureau or dressing-case, yet providing all the necessary facilities for toilet 25 purposes; and it is to the attainment of this result that the present invention is directed.

The improved structure consists, briefly, in a 30 toilet-stand containing a set of drawers and the ordinary mirror, and having a slab or top 35 upon which are arranged "deck" drawers or receptacles, so positioned as to leave a central space thereon, below the surface of which top there is provided a wash-bowl that is concealed when not in use by a level cover, which 40 may be moved to one side without disarranging any other portion of the stand; to expose the wash-bowl and the fresh-water faucet for use. Below the wash-bowl there is arranged a closet for a waste-receptacle, and closed by a 45 door having a mirror. It also consists in a flexible horizontally-sliding cover, combined with a slab or top that is adapted for use as a table, and for concealing an opening in said top.

50 A practical embodiment of this improved structure is illustrated in the accompanying drawings, in which—

Figure 1 is a perspective view of a toilet-stand in its normal condition, embodying the 55 improvements; Fig. 2, a vertical central section of the same, taken through the wash-bowl

and closet for the waste-receptacle, showing the movable cover in its closed position; Fig. 3, a like view of a portion of the stand, showing the cover moved so as to expose the wash-bowl. Fig. 4 is a vertical section of a portion of the stand, taken on a plane with the front of the stand, showing particularly the deck receptacles, wash-bowl, and side drawers; and Fig. 5, a like view showing a modified arrangement of the movable cover or top.

Referring to these drawings, it will be seen that the structure consists of a stand, A, supporting in the usual manner a mirror, B, said stand being provided with a marble or other 60 top, a, upon which are mounted deck receptacles b c, arranged upon each side of the top so as to leave a central space, e. The stand A is also provided with a series of side drawers, f g h and i j k, a lower drawer, l, extending the 65 width of the stand, and a centrally-arranged closet, m, the door of which may carry a mirror, as shown, or be simply paneled, according to the taste of the maker.

The center of the slab or top a at the space 70 e is removed and provided with a wash-bowl, C, that is secured to its under side in any suitable manner, and having a central waste-outlet, o, and an overflow, p, projecting into the closet m, in which a waste-receptacle, D, is provided to catch the water allowed to flow from the bowl. A shallow receptacle, E, may be employed in which the waste-receptacle will stand, 75 so as to catch any water that might otherwise fall on the closet-floor, or overflow the bucket. 80

The deck receptacle b has an ordinary drawer, as shown, while the receptacle c is provided with a tank, F, for containing fresh water, its cover n being removable, so that access may be had to it for refilling or for 85 cleansing purposes. This tank at its lower end is provided with a conduit, u, that passes through the top a of the stand, and along, either in a groove therein or on its under side, to the wash-bowl, where it has a faucet, v, as 90 clearly seen in Fig. 4. This conduit u might, of course, be jointed between the bottom of the tank and bowl, so as to permit the removal of the tank from its receptacle c for repair and 95 other purposes.

Between the deck receptacles b c, and directly over the slab or top a, there is provided 100

a movable cover, G, which, when the wash-bowl is not in use, forms a perfectly level top or table that completely conceals the bowl, and which may be conveniently moved to expose it for use. This cover G slides in grooves 9, (see Fig. 4,) formed in the sides of the receptacles b c, which are continued by a curve, 10, down alongside of the back board of the stand A to a stop, 12. In order to enable the cover to follow these grooves 9 it is formed of a number of narrow slats, w, that are tongued and grooved, as shown, and firmly secured together at their under sides by a flexible sheet of rubber or other similar material, 15 as leather or canvas, which, when the cover is in its closed position, Fig. 2, will form a tight and even surface and of considerable strength.

The forward slat of the cover G is preferably made somewhat wider than the remaining slats for effective operation in pulling the flexible cover over the opening in the slat or top, and preventing it from doubling on the curve. This forward slat is provided with a strip, y, 25 that extends slightly beyond its edge, so as to overlie a permanent front strip, x, concealing the forward end of the cover and affording a convenient hand-piece, by which the cover may be slid back and forward.

Between the deck receptacles, and at the back of the stand over the sliding cover G, is a narrow box, H, provided with a hinged cover, that may be employed for holding toilet articles, such as combs, brushes, soap, &c. The 35 bottom of this box lies close to the upper line of the sliding cover, and forms a finish at the back of the stand, concealing the turn made by said sliding cover, and might also form a stop against which the handle or strip y may abut 40 to prevent the cover sliding too far. While this arrangement of cover for closing the opening in the slab or top and concealing and exposing the wash-bowl affords a perfect horizontal top or table thereto when closed, and a 45 convenient mode of removing it, the arrangement may be such that the cover G can be directed upward to the back of the stand, as shown by dotted lines in Fig. 2; or, as in Fig. 5, the cover may be formed in two pieces divided centrally, each piece being arranged to slide sidewise in recesses formed in the under side of the deck receptacles, in either of which arrangements by a simple sliding movement the opening in the top or slab and the bowl is 55 concealed or exposed without disturbing any other portion of the stand.

While the slats w, composing the sliding and flexible cover G, have been described as secured together by a backing of flexible material, it 60 is obvious that they may be fastened by elastic cords running through them from back to front, and suitably secured at each end to the end slats.

The space in the stand may be further utilized by forming a shelf, 13, under the bowl, 65 that is concealed by a drawer, d, having a

front and two side pieces, but no bottom or back.

From the foregoing description it will be seen that a structure of great simplicity is provided in which two useful articles of furniture—a bureau and a wash-stand—are combined in such a manner that its general appearance closely resembles an ordinary bureau or dressing-case, and which contains ample drawer-space without an increase in size.

While the flexible horizontally-sliding cover is shown as employed to conceal a wash-bowl, it is obvious that it might be employed in connection with the top of any article of furniture, stand, or other device—such as a water-closet seat or a butler's sink—in which it is desired to conceal and expose an opening therein, and when closed afford a suitable top or table for use in the ordinary way.

I am aware that sliding tops have heretofore been used in connection with wash-bowls; but such tops have passed at some distance above the wash-bowl in curved grooves or lines, thus consuming considerable vertical space; and I am also aware that deck receptacles having a central horizontal top concealing a wash-bowl have been provided; but in such structures one of the deck receptacles was connected to said top, and was hinged so that the whole turned up vertically to one side of the stand. In my improved structure both of the deck receptacles are utilized and remain undisturbed, and upon which toilet articles may rest, while a sliding cover or top for the wash-bowl is provided whose flat surface is moved in a horizontal plane, and which may be employed, when closed, as a table as in simple ordinary bureaus.

It may sometimes be preferred to use but one deck receptacle, and in such case it might be arranged at the back of the bowl, parallel with the mirror, taking the place of the box H. Fresh water may also be led directly from the water-service, and the waste be connected with a sewer by any suitable connections; and, further, the bowl and closet might be arranged at one side of the stand, and the drawer on one side be thus widened, the others being omitted, as in an ordinary commode.

What I claim is—

1. In a combined bureau and wash-stand, the combination, with its deck receptacles, as b c, and a bowl arranged therebetween, of a flat cover arranged to slide between said receptacles to cover and uncover said bowl, substantially as described.

2. A combined bureau and wash-stand, consisting of a slab or top, a, provided with a wash-bowl beneath its surface and having deck receptacles, as b c, on either side thereof, and a horizontal flexible cover, G, arranged to slide between said receptacles over said bowl to cover and uncover the same, substantially as described.

3. A combined bureau and wash-stand, consisting of a stand provided with drawers, a

slab or top, *a*, having a bowl, *C*, arranged beneath its surface and in a fixed position with relation to the stand, a deck receptacle, as *c*, providing a water-tank having communication 5 with said bowl, and a flat cover, *G*, sliding horizontally above said slab to cover and uncover said bowl, substantially as described.

4. A combined bureau and wash-stand, consisting of a stand provided with drawers and 10 a central closet, a slab or top, *a*, provided with a wash-bowl, *C*, beneath its surface, deck-receptacles *b c*, mounted on said slab, one on either side of said bowl, and a flat cover, *G*, arranged to slide on said slab and between the 15 deck receptacles, substantially as described.

5. A combined bureau and wash-stand, consisting of a stand provided with drawers and a central closet, a slab or top, *a*, provided with a wash-bowl, *C*, beneath its surface, deck receptacles *b c*, mounted on said slab, one on either side of said bowl, one of which receptacles, as *c*, containing a fresh-water tank and provided with connections with the bowl, and a faucet to supply water thereto, and a flat 20 cover, *G*, arranged to slide on said slab and between the deck receptacles to cover and uncover said bowl and faucet, substantially as described.

6. A combined bureau and wash-stand, consisting of a slab or top, *a*, provided with a wash-bowl, *C*, beneath its surface, separate deck receptacles *b c*, mounted on said slab, one on each side of said bowl, a receptacle, *H*, mounted over said slab at the rear of the bowl and between said deck receptacles, and 30 a horizontal flexible cover, *G*, arranged to slide between said deck receptacles under said receptacle *H*, and over said bowl to cover and uncover the same, substantially as described.

7. A combined bureau and wash-stand, consisting of a stand provided with drawers, a slab or top, *a*, having a bowl, *C*, and a fresh-water faucet arranged directly beneath its surface and in a fixed position with relation to the stand, a deck receptacle, as *c*, providing a water-tank in communication with said faucet, and a flat cover, *G*, sliding horizontally above said slab to cover and uncover the bowl and faucet, substantially as described.

In testimony whereof I have hereunto set 50 my hand in the presence of two subscribing witnesses.
